(**) Term: **14 Years**

(57) CLAIM

(21) Appl. No.: **29/156,684**

The ornamental design for a liquid hardener agitator, as shown and described.

(22) Filed: **Mar. 5, 2002**

DESCRIPTION

(30) Foreign Application Priority Data

Nov. 29, 2001 (KR) 2001-33585

FIG. 1 is a perspective view of the liquid hardener agitator according to the invention;

(51) LOC (7) Cl. **15-03**

FIG. 2 is a front view thereof;

(52) U.S. Cl. **D15/10**

FIG. 3 is a rear view thereof;

(58) Field of Search D15/21, 10, 627-629;
106/74, 76, 900; 366/155.1; 405/263, 264,
266, 269; 166/292, 293; 111/122, 7.1, 7.4

FIG. 4 is a left-side view;

(56) References Cited

FIG. 5 is a right-side view; and,

FIG. 6 is a plane view.
